ABSTRACT: A flashgun for mounting various flashbulbs and flashcubes is shown having a housing with a first socket into which the flashcube is inserted. A resiliently mounted U-shaped locking member yields as the flashcube is inserted between the pawled arms thereof for locking the flashcube against the urging of an ejection spring within the socket. Depression of a pushbutton contacts the resiliently mounted locking member and frees the flashcube for ejecting it from the socket. A second socket is provided into which various-sized flashbulbs are inserted between a pair of pivoted holding members mounted on opposite sides of the socket. A pair of base contact members engage the flashbulbs, for urging the base of the flashbulbs against the inner edges of the holding members. Depression of the pushbutton contacts the pivoted holding members and frees the flashbulb for socket ejection.

MOUNTING MEANS FOR VARIOUS FLASHBULBS AND FLASHCUBES WITHIN A PHOTOGRAPHIC FLASHGUN

The present invention relates to a photographic flashgun having a socket for holding a flashcube and a socket for holding various flashbulbs and, more particularly to a mounting means by which a flashcube may be mounted in a rotary turret, intermittently rotated, for successively facing the flashcube toward an object to be photographed or a flashbulb may be mounted for facing the object to be photographed.

A conventional flashcube is generally a cube-shaped unit having four flash faces with four built-in flashbulbs which must be intermittently rotated so that any one flash face is faced, at every limited rotation, to the object to be photographed. Thus, the socket for the flashcube should be rotated and stopped in four successive positions so that the four flash faces are each faced accurately toward the object to be photographed. The flashcube socket is, further, required to be easily handled during the mounting and detaching operation of the flashcube. In the prior art the rotation control of a flashcube-mounting flashgun becomes a large-sized one and consequently the conventional flash attachment with such prior rotational control is, necessarily, a large, weighted construction unhandy to carry about. Further, the flashguns of the prior art are not capable of mounting both flashcubes and flashbulbs within a singularly controlled flashgun.

Accordingly, it is an object of the present invention to provide an improved flashgun-mounting means for various flashbulbs and flashcubes.

Another object of the present invention is to provide a flashgun with a flashcube rotation control in which the limited rotational movement of the flashcube is surely controlled and in which the construction is simple so that the flashcube socket incorporated with this control becomes a small, light unit.

A further object of the present invention is to provide a flashgun for mounting flashbulbs and flashcubes with a single simplified method of ejecting the flashbulb and flashcubes therefrom.

Still a further object is to provide an improved flashgun-mounting socket for flashbulbs and flashcubes which is simple in construction, low in cost, and dependable in operation.

In accomplishing these and other objects, there is provided a flashgun having a flashbulb socket with a pair of flashbulb-holding means pivoted on opposite sides of a guide opening located within the socket. The flashbulb-holding means effectively close the guide opening from the inside. As a flashbulb is inserted between the flashbulb-holding means into the guide opening, it engages base contact means which are resiliently urged against the flashbulb. The flashbulb is inserted until the opposite inner edges of the flashbulb-holding means engage and hold the flashbulb against the urging of the base contact means for retaining it within the socket.

A flashcube socket is also provided into which a flashcube having a depending cylindrical post with retaining lugs or projections extending laterally therefrom is inserted. Each projection is arranged with the lower face thereof formed as an inclined ramp. A flashcube-locking member, in the form of a U-shaped element having ramped pawls upon the end of each of the legs, is adapted to be abutted against the corresponding ramps on the projection of the inserted flashcube. The flashcube-locking member is reciprocatively arranged within the flashcube socket against a detent spring, while an ejecting spring is arranged to yield as the flashcube is inserted into the socket. As the flashcube is thrust into the socket against the ejecting spring, the ramps of the flashcube projections are forcibly pressed against the corresponding ramps on the pawls of the flashcube-locking member for driving that member laterally against the detent spring. The flashcube-locking member then returns to its initial position for engaging the pawls over the flashcube projections and restraining the flashcube against the dislodgement force exerted by the ejecting spring. Ejection of both the flashbulbs or the flashcube is achieved by depressing a single pushbutton.

Other objects and many of the attendant advantages of the present invention will appear from the following description, when considered in combination with the accompanying drawings, wherein:

5 FIG. 1 is a side elevational view, partially in cross section showing the improved photographic flashgun in which the present invention is embodied;

FIG. 2 is an exploded perspective view of a flashcube socket assembly;

10 FIG. 3 is an exploded perspective view of a rotary current of carrier for holding a flashcube;

FIGS. 4A and 4B are top and bottom views of the rotary turret;

15 FIG. 5 is an exploded perspective view of a flashbulb socket assembly for holding various flashbulbs;

FIG. 6 is a diagrammatic view showing a condition where a flashbulb is held or retained;

FIGS. 7A, 7B, 7C and 7D are top plane views illustrating four successive stop positions of the rotary turret;

20 FIG. 8 illustrates operation of the rotary turret; and

FIGS. 9A, 9B and 9C are schematic views showing the operational relationship between the flashcube socket assembly and the flashbulb socket assembly.

25 Referring now to the drawings, FIG. 1, illustrating a flashgun in which a flashbulb A and a flashcube B may be inserted and used selectively or concurrently. A main housing 1 of the flashgun receives therein a horizontally disposed flashbulb socket assembly, which is generally shown at 2, and a vertically disposed flashcube socket assembly which is generally shown at 3. The flashcube socket assembly 3 is located just above the flashbulb socket assembly 2. The main housing 1 is also provided, on the outer bottom face thereof, with a mounting device 5 having a coupling plate 4 adapted to be connected with an accessory shoe of a camera, not shown. A flashbulb socket member 6, which is an essential component of the flashbulb socket assembly 2, is closely fitted in an opening 7 provided in a front wall of the housing 1. The socket member 6 has a socket guide opening 8 to universally receive therein a base A₁ of the flash lamp A, for example of the AC type, the M type or the bayonet type.

30 The flashcube socket assembly 3 has a rotary turret 9, loosely fitted at its upper portion in an opening 10 of a top wall 1B of the housing 1. The top face of the turret 9 is exposed out of the top wall 1B and positioned in coplanar alignment with the outer face of the top wall 1B. The rotary turret 9 is, further, provided in the top face thereof with a crossed slot 11 which may receive and retain a depending post projecting downwardly from the bottom of the flashcube B. The opening 40 10 of the housing 1 is also provided at its upper circumferential edge with an annular recess or groove 12 to receive a cylindrical skirt portion B₂ projecting downwardly from the bottom of the flashcube B. The cylindrical skirt portion B₂ is surrounded therearound with electrical terminals, not shown.

45 50 55 It will be understood that the electrical terminals are exposed outwardly from electrical contact with a pair of electrical terminals within the forward portion of the annular recess.

The flashcube socket assembly 3 will be now described in detail with reference to FIG. 2. A baseplate 13, which is of 60 substantially rectangular configuration, has at the center thereof an aperture 15 in which is inserted and journaled a rotating shaft 14 depending downwardly from the bottom of the rotary turret 9. Between the rotary turret 9 and the baseplate 13 is interposed an accumulator spring assembly to 65 give a turning force to the rotary turret 9. The accumulator spring assembly comprises a downwardly opened cup-shaped retainer 17 and a spiral spring 18 received in the retainer 17 with the spiral spring 18 being wound up in a counter-clockwise direction, as taken from the top view thereof. The 70 spiral spring 18 has an innermost end 18A engaged in a slit 19 provided in the rotating shaft 14 and has an outermost end 18B welded to the inner peripheral surface 17A of the retainer 17. A lug 17B is formed on the lower end of said retainer 17 and is adapted to extend through and engage with an engaging 75 slot 20 in the baseplate 13.

The rotary turret 9 comprises an upper part or flashcube mounting part 21 and a lower part or cam part 22, as shown in FIG. 3. These upper and lower parts 21 and 22 are welded, adhered or otherwise suitably assembled to each other. The flashcube-mounting part 21 is provided on the peripheral sidewall thereof with an annular shouldered or stepped portion 23 to prevent the rotary turret 9 from slipping out of the housing 1 and is provided at the center thereof with the crossed slot 11 adapted to receive therein the depending post B₁ of the flashcube B. On the lower surface of the flashcube-mounting part 21 are provided radially spaced, parallel channels or grooves 25 and 25 which are merging with the radially opposed slots 11A and 11A of the crossed slot 11, respectively. A flashcube-locking means 24 is provided, which is composed of a detent element 26 having a "U"-shaped configuration to form a pair of arms which are slidably received in the channels or grooves 25 and 25. The free ends of the arms are terminating in upright ramped pawl members 26A and 26A which are extending upwardly in said radially opposed slots 11A and 11A and are engageable by radially opposite projections B₃ B₃ which extend laterally from opposite sides of the depending post B₁ to secure the flashcube B in the socket. Detent springs 27 are each interposed between the detent elements 26 and the blind end of the channel 25 to positively position the upright pawl members 26A within the radial slots 11A. The lower part or cam part 22 is provided on its upper surface with an upwardly projecting pin 27 which is aligned with the center of said crossed slot 11 to guide the post B₁ of the flashcube B. On the upwardly projecting pin 27 are mounted a coiled ejection spring 29 and a washer member 28 which is loosely fitted in another pair of radially opposed slots 11B adjacent to the first pair of slots 11A and 11A to provide means for ejecting the flashcube B from the flashcube socket assembly 3.

It will be seen from FIG. 4B that the cam part 22 is provided on the bottom thereof with four sectors arranged around the periphery of the cam part 22 in equally spaced end-to-end relationship at every angle of 90°. Three sectors from among said four sectors consist of cam elements or downwardly projecting ribs 31A, 31B and 31C each of which has a pair of parallel curved cam surfaces 30A and 30B which are substantially radially spaced. The cam surfaces 30A and 30B are designed to be radially offset in an inward direction as they are advanced in a counterclockwise direction of the cam part 22, when viewed in FIG. 4B. The residual sector is used as a block 32 to engage with a stopper, as will be hereinafter described, thereby preventing the rotary turret 9 from excess rotation. It will be thus apparent that between adjacent sectors of the four sectors 31A, 31B, 31C and 32 is provided a radial passage for permitting the stopper to retreat radially along a sector-dividing line, not shown. As will be apparent from the following operational description with respect to the present invention, the parallel curved cam surfaces 30A and 30B may be formed by means of channels or grooves rather than the ribs. In this case, the radial passages will be of the conventional relief recess type.

Located adjacent to the peripheral wall of the rotary turret 9 and assembled with the baseplate 13 is an operating element 37 which slips in a guide channel or recess 34 provided on one side of the baseplate 13. The operating element 37 is supported with a supporting member 36 secured to the upper face of the baseplate 13 through machine screws 35A and 35B. The operating element 37 is forcibly urged by a compression spring 38, interposed between the operating element 37 and the supporting member 36, towards a direction where the operating element 37 may be kept apart from the rotary turret 9. The operating element 37, thus assembled with the baseplate 13, comprises an arm 37A for operating the flashcube-holding means 24, and a stopper arm 37B which is provided with a traverse groove or channel 39 having the substantially same width as that of the ribs or cam elements 31A, 31B and 31C. Against the rear face of the operating element 37 may be abutted a rocker arm connected to a pushbutton 47, which will be hereinafter described in detail.

Reference will be now made to FIG. 5 in which the flashbulb socket assembly 3 is illustrated in detail. A pair of flashbulb-holding pieces 42 and 42 are provided within the socket guide opening 8 of the socket member 6. The flashbulb-holding pieces 42 and 42 are arranged in radially opposite relationship and are pivotally mounted on pins 40 and 40 supported in the socket member 6. The flashbulb-holding pieces 42 and 42 are, further, normally biased by means of springs 41 and 41 so as to choke up the socket guide opening 8. The holding pieces 42 and 42 are quite similar to each other in their structure so that each piece may normally choke up one-half of the socket opening 6. They are each comprised of a main part 42B having the innermost end 42A engageable with the base A₁ of the flashbulb A and of tail part 42C formed integral with said main part 42B. The tail part 42C extending outwardly at moderate angles from the main part 42B. Base contact members 43 are provided with springs 43A for urging the base A₁ of the flashbulb A against the ends 42A of the holding pieces 42. Those contact members 43 serve as electrical contacts, as more fully described in our copending U. S. Patent application, Ser. No. 802,545 filed Feb. 26, 1969. An ejector 44 is further provided at the back of the socket member 6. The ejector 44 comprises a Y-shaped member having a pair of arms 44A and 44A extending forwardly through the socket member 6. The arm 44A and 44A engage the tail parts 42C of the flashbulb-locking pieces 42 and 42, thus permitting them to release the base of A₁ of the flashlamp A. Coiled springs 45 and 45 surround arms 44A and 44A to bias the ejector 44 backwardly in such a manner that the ejector 44 may be normally returned to its inoperative position. A rearwardly projecting foot 44B of the ejector 44 is extended to the vicinity of a rear wall 1C of the housing 1 where it engages the pushbutton 47. It should be noted that the coiled springs 44A and 44A acting on the ejector 44 must be smaller in spring constant than the coiled compression spring 38 acting on the operating element 37.

Approximately halfway between the flashbulb socket assembly 2 and the flashcube socket assembly 3, an opening 46 is provided on the rear wall 10 of the housing 1 to receive 40 therein the pushbutton 47 with its rearmost extremity being projected rearwardly and exposed out of the housing 1. The pushbutton 47 has a foremost pointed end on which rocker arm 49 is pivotally supported through a connecting pin 48 midway between its opposite extremities. The extremities are 45 respectively engageable with the operating element 37 of the flashcube socket assembly 3 and with the ejector 44 of the flashbulb socket assembly 2. In the illustrated construction, one extremity 49A of the rocker arm 49 abutted against the operating element 37 of the flashcube socket assembly 3 is bent into an L shape so that the extremity 49A may become a fulcrum during initial depression of the pushbutton 47. It will be, however, understood that the rocker arm 49 may be bent at both of the opposite extremities.

With the flashbulb socket assembly 2 arranged and assembled as described above, the flashbulb A, for example of bayonet type, is thrust into the socket guide opening 8 with its base A₁ forcing the opposed flashbulb-holding pieces 42 and 42 open by swinging rearwardly with their respective pin 40 as the fulcrum. The flashbulb A, thus thrust into the socket opening 8, will be securely held or locked by means of the diametrically opposed holding pieces 42 and 42 with their associated innermost ends 42A and 42A being snap fitted or engaged to an annular groove on the base A₁. The flashbulb is urged forward against these innermost ends 42A by means of the base contact member 43. This applied irrespective of the type of the flashbulb utilized within the socket.

Now, the flashcube B is mounted on the flashcube socket assembly 3 with the depending post B₁ being depressed into the crossed slot 11 formed in the rotary turret 9. Thus, the upright ramped pawl members 26A and 26A of the flashcube-locking member 24 are at first driven away from the radially opposed slots 11A and 11A into the channels or grooves 25 and 25, by means of the ramped, radially extending projectors 70 B₃ and B₃ on the post B₁, as it is depressed in this socket as-

sembly. The pawls are restored into the slots 11A and 11A by action of the coiled detent springs 27 and 27 when the projections B₃ and B₃ are further depressed inwardly across the level of the pawl members 26A and 26A. The projections B₃ are then restrained against their upward movement, urged by the ejection spring 29. Thereafter, a clockwise rotational movement of the flashcube B through an angle of 270° when viewed from above, causes energization of the spiral spring 18. At the same time, the stopper arm 27B runs in the passage 33D, 33C, 33B and 33A to engage the inwardly offset end of the rib 31A with the stop arm 37B. The result is that the first flashbulb in the flashcube B is now accurately faced against the object to be photographed.

It will be understood from the foregoing that, when the flash switch in the camera (not shown) is actuated to close the flash circuit, the flashbulb A or a first flashbulb within the flashcube B is ignited for producing a brief but intense flash of light to illuminate the object to be photographed. The following will explain, with reference to FIG. 9, what operation or operations may be accomplished to effect removal of the flashbulb A, rotary feed of the flashcube B, and the eventual removal of the flashcube B.

In the illustrated embodiment, the arrangement is designed so that the spring 38 acting on the operating element 37 has a larger spring constant than the spring constant of the springs 45 and 45 acting on the ejector 44. Depression of the pushbutton 47 causes the rocker arm 49 to swing with its bent extremity 49A as the fulcrum. Depression of the pushbutton 47, therefore, results in a forward sliding movement of the ejector 44 against the coiled springs 45 and 45, thus permitting the foremost ends 44A and 44A thereof to forwardly thrust the tail ends 42C and 42C of the opposed flashbulb holding pieces 42 and 42 which causes the opening thereof. The flashbulb A is in this way, brought into a released condition and at the same time ejected from the socket opening 8 by the spring-loaded base contacting members 43. Thereafter, the ejector 44 is moved forwardly until the tail parts 43C make contact with the stopping face on the socket member 6. Finally, the ejector 44 ceases to move forward as shown in FIG. 9B. Further depression of the pushbutton 47 causes the rocker arm 47 to rock with the point engaging the ejector 44 acting as the fulcrum, as shown in FIG. 9C. At this point, the operating element 37 slides forward along the guide channel 34. The traverse channel 39 in the operating element 37 is then aligned with the rib 31A and consequently the rotary turret 9 will be in unlocked condition. In this condition, the rotary turret 9 will be free to rotate in the counterclockwise direction, as viewed from above. However, since the rib 31A has the outer cam surface 30B spirally oriented as previously described, the rotary turret 9, following its limited rotation, should be locked against rotation with the rib 31A making contact with the side edge of the channel 39 (shown in FIG. 8). The rotary turret 9 is held in such condition so long as the pushbutton 47 is forcibly depressed. Subsequently, as soon as the pushbutton 47 is released, the other side edge of the traverse channel 39 is urged against the inner cam surface 30A extended in parallel with said outer cam surface 30B. The operating element 37 is then forcibly biased rearwardly by the coiled compression spring 38 thus allowing the rotary turret 9 to be rotated under a damping action. When the stopper arm 37B arrives at the passage 33B in a manner described above, the innermost end face of the rib 31B is abutted against the stopper arm 37B whereby the rotary turret 9 ceases at a position where the second flashbulb is accurately faced to the object to be photographed.

It will be thus apparent from the foregoing that the limited rotation of the rotary turret 9 is repeated each time a flashbulb within the flashcube is ignited for producing a brief but intense flash of light. After the final or fourth flashbulb has been ignited or burned, the depression of the pushbutton 47 permits the arm 37A of the operating element 37 to engage with the detent element 26 so as to press inwardly the detent element 26 along the channels or grooves 25 and 25. As a result, the 75

upright pawl members 26A and 26A currently in locking position are moved towards the channels 25 and 25 to thereby release the radially opposed projections B₃ and B₃ so that the flashcube B may be driven out of the rotary turret 9 by means of the coiled ejection spring 29.

Having now described the present invention, it will be seen that the improved flashgun may become extremely compact so that the flashbulb socket assembly and the flashcube socket assembly may be preferably constructed and arranged within a flashgun so as to be portable, compact, and lightweight. The flashcube-rotation control is simple in construction, thus trouble free, and highly reliable in positioning of the flashbulb. According to the present invention, further, there is no fear that the flashcube may be damaged due to the intense percussion against the flashcube because the rotary turret control procedure is accomplished under a damping action against the rotary turret. The rotary turret control of the present invention has further advantages too numerous to mention, for example, an advantage that removal operation of the flashcube is easily achieved by merely providing the simple operating element for the flashcube-locking means.

Obviously, many modifications and variations of the present invention will become apparent to those skilled in the art in light of the above. Therefore, the present invention should be limited only by the appended claims.

The embodiments of the invention in which an exclusive property or privilege is claimed are defined as follows:

1. A photographic flashgun for mounting flashcubes therein, comprising:
housing means;
flashcube socket means within said housing means;
said flashcube socket means including a baseplate;
rotary turret means for receiving said flashcubes mounted upon said baseplate;
urging means connecting said rotary turret means to said baseplate means for exerting a rotary force thereon;
cam elements equally spaced about the periphery of said rotary turret means for forming passageways therebetween;
an operating stop element slidably arranged to pass between said passageways having a slot therein; radially said cam elements having parallel camming surfaces which curve outwardly and radially from the rotational axis of said rotary turret means along which said slot within said operating stop element is arranged to pass;
one of said cam elements having nonparallel camming surfaces,
said operating stop element resiliently mounted to inwardly slide along one of said passageways for allowing said cam element to pass through said slot upon alignment therewith thereby allowing the rotation of said turret means under the urging of said urging means until said operating stop contacts the next cam element whereupon said sliding operation of said operating stop may be repeated to allow rotation of said turret means until said one of said cam elements having nonparallel camming surfaces is reached for permanently stopping said rotation thus rotatively controlling the facing of said flashcubes.

2. A photographic flashgun for mounting flashcubes therein as claimed in claim 1, additionally comprising:

spring ejection means for urging said flashcubes from said rotary turret means;
flashcube-locking means slidably mounted within said rotary turret means having pawled leg portions with the uppermost faces thereof formed as inclined ramps for slidably engaging said flashcubes;
urging means attached to said flashcube-locking means arranged to yield as said flashcubes as received within said rotary turret means and arranged to hold said locking means in locked arrangement against the urging of said spring ejection means after said flashcubes as full received within said rotary turret means, and
pushable means mounted within said housing means arranged to contact said flashcube-locking means as said

rotary turret means is stopped by said cam element having nonparallel camming surfaces and said operating stop; whereby depression of said pushable means moves said flashcube-locking means for ejecting said flashcubes from said rotary turret means.

3. A photographic flashgun for mounting flashcubes therein as claimed in claim 2, additionally comprising:

flashbulb socket means within said housing means for mounting various-sized flashbulbs having varying base sizes;

a pair of flashbulb-holding means pivotally supported within said flashbulb socket means for receiving said various-sized flashbulbs therebetween;

base contact means resiliently arranged to contact said base of said flashbulbs, as said flashbulbs are received between said flashbulb-holding means, for urging said flashbulbs against said pivotally supported flashbulb-holding means thereby holding said flashbulbs therebetween;

movable flashbulb ejector means engaging said flashbulb-holding means for causing said flashbulb-holding means to open upon movement of said movable ejector means for ejecting said flashbulbs from said socket means; and said pushable means contracting said movable flashbulb ejector means for moving same and ejecting said flashbulbs from said flashbulb socket means.

4. A photographic flashgun for mounting various flashbulbs having varying base and bulb sizes, and for mounting flashcubes having a depending cylindrical post with ramps projections extending laterally therefrom, comprising:

housing means;
flashbulb socket means within said housing means;
a pair of flashbulb-holding means pivotally supported within

said flashbulb socket means for receiving said various-sized flashbulbs therebetween;

base contact means resiliently arranged to contact said base of said flashbulbs, as said flashbulbs are received between said flashbulb-holding means, for urging said flashbulbs against said pivotally supported flashbulb-holding means thereby holding said flashbulbs therebetween;

movable flashbulb ejector means engaging said flashbulb-holding means for causing said flashbulb-holding means to open upon movement of said movable ejector means for ejecting said flashbulbs from said socket means;

flashcube socket means within said housing means;
spring ejection means for urging said flashcubes from said flashcube socket means;

flashcube-locking means slidably mounted within said flashcube socket means having pawled leg portions with the uppermost faces thereof formed as inclined ramps for slidably engaging said ramped projections of said flashcubes;

urging means attached to said flashcube-locking means arranged to yield as said flashcubes are received within said flashcube socket means and arranged to hold said locking means in locked arrangement against the urging of said spring ejection means after said flashcubes are fully received within said socket means; and

pushable means connected with said movable flashbulb ejector means and said flashcube-locking means wherein depression thereof causes the movement of said movable flashbulb ejector means and flashcube-locking means for ejecting said flashbulbs or said flashcubes from said housing means.
